UNITED STATES PATENT OFFICE.

AUGUST G. MACK, OF OOLITIC, INDIANA.

AIR HAMMER.

Application filed January 6, 1920. Serial No. 349,692.

To all whom it may concern:

Be it known that I, AUGUST G. MACK, a citizen of the United States, residing at Oolitic, in the county of Lawrence and State 5 of Indiana, have invented certain new and useful Improvements in Air Hammers; and I do hereby declare the following to be a full, clear, and exact description of the invention, such as will enable others skilled 10 in the art to which it appertains to make and use the same.

This invention relates to new and useful improvements in pneumatic hammers and more particularly to a handle for said type 15 of hammer and has for its primary object the provision of means which will eliminate excessive vibration created by the hammer and received by a person's hand while operating the device and which has proven very 20 injurious to the person or operator on continuous use of such a device.

Another object of this invention is the provision of a handle for pneumatic hammers of the above stated character, which 25 can be easily and quickly applied to an ordinary pneumatic hammer without altering the construction thereof and which shall be simple, durable and efficient, and which may be manufactured and sold at a comparatively 30 low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following 40 description and accompanying drawing, in which:—

Figure 1 is a side elevation of a handle constructed in accordance with my invention and illustrating the same applied to a pneumatic hammer,

Figure 2 is a vertical sectional view of the same,

Figure 3 is a side elevation illustrating a modified form of handle and showing the 50 same applied to a pneumatic hammer,

Figure 4 is a vertical sectional view of the same,

Referring in detail to the drawing, the numeral 1 indicates as an entirety an ordinary pneumatic hammer including a body 2 having connected at one end the usual air

supply hose 3 and a chuck 4 at its other end to receive and grip an ordinary tool used in connection with the hammer. The chuck 4 forms a part of the body 2 of the hammer 60 and defines an annular shoulder 5 and the other end of said body is reduced as illustrated at 6 to define an annular shoulder 7. The foregoing description relates to a well known construction of pneumatic hammer 65 and to which my invention is applied. A handle 8 consisting of a tubular body 9 has formed on one end an inwardly directed flange 10 that receives the reduced end 6 of the body 2 of the hammer and is spaced 70 from the annular shoulder 7. A cushioning washer 11 is interposed between the shoulder 7 and the inwardly directed flange 10 and this washer is constructed from rubber or any other material suitable for the purpose. 75 The body 9 of the handle 8 is of such a size that it will permit the body 2 of the hammer to have free movement therein and the other end of said body 9 is reduced and screw threaded to form an attaching neck 12. 80

A cap 13 is threaded to the neck 12 and has formed thereon an inwardly directed flange 14 which is spaced from the annular shoulder 5 of the body 2 forming an oil space and also permitting the hammer body 85 2 to have play within the handle 8 so that the excessive vibration set up by the pneumatic hammer when in operation will be expended by the movement permitted of the hammer 2 within the handle 8 thereby reducing the vibration received by a person's hand gripping the handle 8.

Referring to my modified form of invention as disclosed in Figures 3 and 4, the hammer 15 consists of a body 16 having a 95 reduced end 17 provided with an exhaust port 18 and said reduced end has connected thereto the usual supply hose 3. The other end of the body 16 is reduced and has slidably mounted therein the plunger 19 adapted 100 to strike the tool carried by the chuck 20. In this instance the chuck 20 is a separate element from the hammer 15.

My modified form of handle includes a cylindrical body 21 which receives the body 16 of the hammer 15 and has one end restricted to form an annular shoulder 22 and an opening 23 to permit the reduced end of the body to extend therethrough.

The reduced end 17 of the body 16 of the 110 hammer 15 is provided with an annular shoulder 24 against which is positioned a

cushioning washer 25 and which washer is adapted to abut the shoulder 22 during the movement of the hammer within the handle. The other end of the handle 21 is internally 5 screw threaded and has threaded connection with the chuck 20 which forms a closure for said end of the handle, and which is spaced from the end of the body 16 of the hammer so as to permit said body of the hammer to 10 move backward and forwardly within the handle 21 and which movement is caused by the excessive vibration set up by the hammer. Owing to the movement permitted the hammer within the handle reduces the 15 vibration to a person's hand gripping the handle 21.

The handle 21 adjacent the restricted end is provided with an exhaust port 26 to permit the exhaust escaping from the exhaust 20 port 18 to pass exteriorly of the handle.

While I have shown and described the preferred embodiment of my invention, it will be understood that minor changes in construction, combination, and arrangement 25 of parts may be made without departing

from the spirit and scope of the invention as claimed.

Having thus described my invention, what I claim is:—

As an attachment for a tool of the class 30 described provided with spaced shoulders, a sleeve to serve as a handle enclosing a part of the tool, said sleeve being in sections separable to permit passage over the tool, each section having a shoulder to engage said 35 shoulders, the sleeve being loose on the tool and having its shoulders farther apart than those of the tool, one of the sections of the sleeve being a chuck, the inner end of the chuck serving as one of the shoulders of the 40 sleeve, the tool having a plunger, and the chuck having a tool retaining recess into which the plunger extends.

In testimony whereof I affix my signature in presence of two witnesses.

AUGUST G. MACK.
